UNITED STATES PATENT OFFICE.

ALBERT C. BUSCHNER, OF NEW YORK, N. Y.

BORDER FOR CUSHIONS AND SIMILAR ARTICLES.

No. 796,561.

Specification of Letters Patent.

Patented Aug. 8, 1905.

Application filed June 3, 1905. Serial No. 263,544.

To all whom it may concern:

Be it known that I, ALBERT C. BUSCHNER, a citizen of the United States, residing at New York city, Brooklyn, county of Kings, and State of New York, have invented new and useful Improvements in Borders for Cushions and Similar Articles, of which the following is a specification.

This invention relates to a border for cushions and similar articles, which is of pleasing appearance, increased strength, and not apt to fray during use.

In the accompanying drawings, Figure 1 is a front view of a cushion provided with my improved border. Fig. 2 is a side view of the border, showing it partly broken away; Fig. 3, a cross-section on line 3 3, Fig. 2; and Fig. 4 an enlarged cross-section through the fold of the border.

The border is composed of a strip of textile fabric which is folded longitudinally along the line a to form a wide rear flap a' and a narrow front flap a'' . The rear flap is thus exposed beyond the edge of the overlapping front flap, and this exposed section, as well as the entire front flap, may be suitably ornamented, as shown. Along the fold a a gathering-string b is drawn through the fabric, by means of which both flaps a' and a'' are uniformly shirred, so that though folded they lie closely against each other. The gathering-string also permits the fabric to be gathered sufficiently to follow the corners of a cushion c , to the edge of which the border is connected along

the fold a . The appearance of my improved border is very pleasing, owing to the combined effects of the upper and lower flaps. Further, the border is of greatest strength and stiffness along the edge of the cushion and, finally, as the gathering-string is placed at a distance from both edges of the fabric the latter are not apt to fray out during use.

What I claim is—

1. A border for cushions and similar articles, composed of a longitudinally-folded strip having a rear flap, an overlapping front flap that is narrower than the rear flap, and a gathering-string at the fold, substantially as specified.

2. A border for cushions and similar articles, composed of a longitudinally-folded strip having a shirred rear flap, an overlapping shirred front flap that is narrower than the rear flap, and a gathering-string at the fold, substantially as specified.

3. A cushion provided with a border composed of a longitudinally-folded strip having a shirred rear flap, an overlapping shirred front flap that is narrower than the rear flap, and a gathering-string at the fold, said border being secured to the cushion along said fold, substantially as specified.

Signed by me at New York city, Manhattan, New York, this 31st day of May, 1905.

ALBERT C. BUSCHNER.
